UNITED STATES PATENT OFFICE

158,674

ELECTRIC IRON

Rhoba Belle Lincoln, East Bakersfield, Calif.

Application July 26, 1949, Serial No. 4,150

Term of patent 7 years

(Cl. D49—6)

To all whom it may concern:

Be it known that I, Rhoba Belle Lincoln, a citizen of the United States, residing at 618 Lincoln Street, Station A, E. Bakersfield, California, have invented a new, original, and ornamental Design for an Electric Iron, of which the following is a specification, reference being had to the accompanying drawing, constituting a part hereof.

Fig. 1 is a side elevational view of an electric iron, showing my new design.

Fig. 2 is a bottom plan view.

Fig. 3 is a front elevational view.

I claim:

The ornamental design for an electric iron, substantially as shown.

RHOBA BELLE LINCOLN.
